UNITED STATES PATENT OFFICE

136,692

DESIGN FOR A FLASH UNIT

Major A. Glueck, Kansas City, Mo.

Application October 28, 1942, Serial No. 108,628

Term of patent 3½ years

To all whom it may concern:

Be it known that I, Major A. Glueck, a citizen of the United States, residing at Kansas City, Jackson County, Missouri, have invented a new, original, and ornamental Design for a Flask Unit, of which the following is a specification, reference being had to the accompanying drawing, forming a part thereof.

Fig. 1 is a front elevational view of a flask unit, showing my new design;

Fig. 2 is a top plan view;

Fig. 3 is a side elevational view of the bottle element shown in full lines in Figs. 1 and 2; and

Fig. 4 is a perspective view thereof.

The essential features of the design reside in the portion shown in full lines.

I claim:

The ornamental design for a flask unit, substantially as shown and described.

MAJOR A. GLUECK.

CERTIFICATE OF CORRECTION.
